UNITED STATES PATENT OFFICE.

FRANCIS H. RICHARDS, OF HARTFORD, CONNECTICUT.

AUTOMATIC WEIGHING-MACHINE.

SPECIFICATION forming part of Letters Patent No. 548,839, dated October 29, 1895.

Application filed March 9, 1895. Serial No. 541,087. (No model.)

To all whom it may concern:

Be it known that I, FRANCIS H. RICHARDS, a citizen of the United States, residing at Hartford, in the county of Hartford and State of Connecticut, have invented certain new and useful Improvements in Automatic Weighing-Machines, of which the following is a specification.

This invention relates to weighing-machines, and more especially to that class of weighing-machines which are adapted for automatically and continuously weighing predetermined quantities of grain or other relatively free-flowing materials, the main object being to provide an effective and accurate automatic weighing-machine of the single-bucket class in which all of the operations of loading and discharging the bucket and opening, closing, locking, and unlocking the valve and the bucket-closer shall be performed by mechanisms comprising improved safety and actuating devices, whereby the operation of the valve mechanism and of the bucket mechanism shall be limited the one by the other, so as to prevent waste and insure the normal operation of the machine, and so as to prevent interference with that proper, predetermined, and necessary sequence of operations which is characteristic of the normal working of a perfectly-organized combination of mechanisms in a machine of this type.

Another object of the invention is to furnish the bucket or load-carrying receptacle of a machine of this class with a closer which shall control a relatively-large bucket-discharge opening as compared with the discharge-openings of buckets as heretofore constructed and which closer shall be supported when in its closed position by the application of a relatively-slight amount of force as compared with that required to maintain shut the closers of such prior machines.

A further object of the invention is to provide reciprocally-effective limiters or stops operative, respectively, for controlling the opening movements of the valve and the bucket-closer, and which limiters shall be so organized that a relatively-slight opening movement of the bucket closer shall impart an accelerated or relatively-greater movement to the valve-opening-movement limiter to in-

stantaneously limit or check the opening movement of the valve, and thereby prevent any material opening movement of the valve while the operative organization of the machine is maintained unless the closer is shut and locked in its shut position.

A further object of the invention is to furnish an improved bucket-carrying mechanism in which the bucket shall be supported by one or more pairs of oppositely-disposed counterweighted beams having their movements in unison, and also to effect the unlatching of the bucket-closer by means controlled by the relatively-rapid descending movement of the poising-arms of the scale-beams as compared with the descent of the bucket.

For the purpose of more perfectly and positively controlling the movements of the several operative parts of the machine the invention also contemplates the provision, in connection with the reciprocally-effective limiters or stops for preventing the opening of the closer when the valve is open, and vice versa, of an actuator for opening the valve, which actuator shall have its valve-opening movement positively controlled, so as to alternate with the closing movement of the valve, and which valve-opening actuator shall be inoperative as such except on the release of the valve by the opening-movement limiter or stop therefor, whereby such valve-opening actuator shall be rendered ineffective as such throughout the major portion of the cycle of operations of the machine and without interfering with the proper working of the other operative mechanisms and devices.

An additional object of the invention is to be found in the provision of means for automatically shifting a portion of the normal bucket-counterpoising mechanism onto the bucket-poising mechanism at a predetermined point in the operation of the machine, and the controlling of one of the functions of the machine by one of the relative movements of such portion of the counterpoising mechanism with respect to the remainder of said counterpoising mechanism. In the present application the return movement of this relatively-movable portion of the counter-

poise mechanism will hereinafter be described as operative for effecting the opening of the valve.

Additional objects of my invention are to be found, also, in the provision of means for obtaining in one machine a very wide range of capacities and for setting the machine to weigh and to read any desired or resultant fractional part of a load.

- 10 As to one of the important features thereof, this invention is in the nature of an improvement upon that shown and described in United States Letters Patent No. 535,729, granted to me March 12, 1895, to which reference may be had; and as to other of the parts thereof many of those features of this machine which are not claimed or are of minor importance are to be found in other prior and concurrent applications for patents.
- 15 In the drawings accompanying and forming part of this specification, Figure 1 is a partial front elevation of a weighing-machine of the class described constructed in accordance with my present invention and showing the machine broken in the center for the purpose of illustrating the same on a large scale, thereby clearly outlining the structure of the same. Fig. 2 is a vertical sectional plan view of the same, and also shows the machine 20 broken in the center for a like purpose. Fig. 3 is an end elevation of the machine as seen from the right hand in Fig. 1, and shows the mechanism at one end of the machine, the several operative mechanisms being in their 25 normal positions with the valve open and delivering the material from the supply-chute into the bucket. Fig. 4 is an end elevation looking from the opposite end of the machine to that shown in Fig. 3, and illustrating the 30 mechanism at such end of the weighing-machine, the several operative mechanisms being in positions corresponding with those shown in Fig. 3. Fig. 5 is an end elevation looking from the same end of the machine 35 as in Fig. 3, the valve being shown in its "drip" position and the other operative mechanisms in the poising position of the machine, parts of the apparatus being removed to more clearly illustrate the construction and operation. Fig. 6 is an end elevation looking from the same end of the machine as in Fig. 4, the valve being shown in the position it assumes at the moment of the cut-off and just prior to the opening of the bucket-closer, and the 40 other operative mechanisms being in positions corresponding with such position of the valve, certain of the parts of the apparatus also being removed to more clearly illustrate the construction and operation of the machine. Fig. 7 is an end elevation looking from the same end of the machine as in Fig. 3, the valve being shown in its closed position and the bucket-closer being wide open with the load discharging from the bucket, and those 45 portions of the counterpoising mechanism and bucket which are illustrated being returned to their normal positions, parts of the

apparatus being removed, also, to more clearly illustrate the operation. Fig. 8 is an end elevation looking from the same end of the machine as in Fig. 4, the valve being closed and the closer open, but nearly closed, the bucket empty, and the valve-opening actuator, which will be hereinafter more particularly referred to, being in position for opening the valve 70 upon the unlocking of the valve by the locking shut of the closer. Fig. 9 is a detail plan view corresponding to a portion of the left-hand end of the machine shown in Fig. 2, and illustrating a slight modification which will 75 be hereinafter described.

Similar characters designate like parts in all of the figures.

The framework for carrying the operative parts of the machine may be of any suitable 85 construction, and is shown in the drawings as comprising two side frames or uprights 2 and 4, mounted upon a chambered supporting-base 3 and connected by a top plate 5, to which a suitable hopper, such as H, is shown secured 90 by means of some holding device, such as fastening-bolts.

The side frames 2 and 4 are shown herein as carrying some suitable beam-supports or V-shaped bearings, such as 20 and 20', for supporting the scale-beams which carry the 95 bucket mechanism, consisting of the bucket and its operative devices.

As a means for supporting the bucket or load-carrying receptacle a pair of oppositely-disposed counterweighted beams are shown at B and B', respectively, as pivotally mounted on beam supports—as, for instance, by means of the pair of pivots or knife-edges 24 and the oppositely-disposed pair of pivots or knife-edges 24'—and as having bucket-supports located intermediate of said beam-supports and adjacent to the corresponding beam-supports, these bucket-supports being shown in the drawings as comprising two remotely-disposed pairs of pivots or knife-edges 15 and 15' and 17 and 17'.

Each of the scale-beams B and B' is shown herein as having a pair of beam-arms joined by a combined connecting-shaft and counterpoise, the counterpoise for the beam B being designated by W and that for the beam B' being designated by W'. Each of the scale-beams, therefore, as is usual, has a bucket-poising portion and a bucket-counterpoising portion. Each of the beam-arms comprises a bucket-poising and bucket-counterpoising member or end, the bucket-counterpoising portions of the beam-arms for the scale-beam B being designated herein by 28 and 28', respectively, and the bucket-counterpoising portions of the oppositely-disposed arms of the beam B' being designated by 29 and 29', respectively.

For the purpose of supporting the bucket 130 from and by the beam-arms the bucket-supports 15 and 15' and 17 and 17' are shown in the drawings as carried on the corresponding beam-arms of the two scale-beams B and B'.

Some suitable means for maintaining the movements of the scale-beams in unison, and hence the movements of the beam-arms in unison, will be employed, and I have shown such means herein as a guide connection between and joining the beams, and preferably comprising one or more connecting-links—such, for instance, as the links 552 and 552', connecting, respectively, the bucket-poising portions 19 and 21 and 19' and 21' of the scale-beams B and B'. These bucket-poising portions of the scale-beams, it will be evident, comprise all those portion of said beams which lie between the supporting knife-edges 24 and 24', by which the beams are sustained.

As a means for obtaining a free movement of each of the connecting-links relatively to the beam-arms which it joins, each of said links is shown herein as having oppositely-concaved supports or bearing-faces—such, for instance, as the journal-openings 553 and 553', for engaging oppositely-disposed pivots or knife-edges 554 and 554'. (Shown herein as carried by and on the inner ends of the bucket-poising portions of the beam-arms.) These knife-edges 554 and 554' are also illustrated herein as forming integral parts of oppositely and transversely disposed members projecting from said inner ends of said beam-arms and having journal portions, substantially filling the corresponding journal-openings in the link, along one of the diameters of said opening. It will be evident that by providing an ordinary knife-edge bearing or journal connection between the link and the beam-arms the friction between these parts will be reduced to a minimum, and that thereby freedom of movement of the beams will be promoted.

The bucket or load-carrying receptacle, which is of the single-chambered type or class, is shown herein as having a relatively-wide central portion and relatively-narrow receiving and discharging openings and as substantially symmetrical at opposite sides of a central horizontal plane passing therethrough, so that the major portion of the load flowing thereto will be sustained adjacent to and below said horizontal plane of the bucket, to thereby lower the center of gravity of the receptacle when loaded to its normal capacity.

The bucket or load-carrying receptacle is pivotally mounted on the oppositely-disposed scale-beams, and is shown herein as having bearing-faces, such as 16, in position for engaging the bucket-supports carried by the scale-beams. In the form thereof herein illustrated each of these bearing-faces is substantially V-shaped, and said bearing-faces correspond in number and position with the knife-edges 15 and 15' and 17 and 17'. For the purpose of evenly balancing the bucket upon the beams the bearing-faces 16 are shown as equidistantly disposed from the center of the receptacle, it being understood that the bucket should be so constructed as

to have no tendency to preponderate in either the one direction or the other, and that the center of gravity of said bucket is substantially in the central vertical plane thereof. The bearing-faces 16 may be carried by the bucket in any suitable manner, and are illustrated in the drawings as supported by brackets or hangers 555, rigidly secured to the ends 75 of the bucket.

The bucket-closer, which is designated in a general way by L, is shown as consisting of a suitably-formed plate or closer proper, such as 75, having a counterweighted arm 79, preferably formed integral therewith, the closer being also illustrated as pivoted at 77 and 78 to the lower side of the bucket and adjacent to one side of the discharge-opening thereof. The closer-plate is preferably formed so as to 85 hold the material being weighed without closing against the edges of the walls of such bucket-discharge opening, but closes under these edges and contiguous to a guard, such as 36, which is secured to the lower side of 90 the bucket in such a position that the contents of the bucket are kept from leaking out without requiring a very close fitting of the parts.

As a means for supporting the bucket-closer, 95 an inverted toggle connection is shown in the drawings as connecting the closer and the bucket, and this toggle connection is so positioned as to be engaged by a closer-latch and held at about the angle of repose of the connection when the latch is in its operative position and the closer is shut. In the form thereof herein illustrated this toggle connection comprises some suitable rocker—such, for instance, as 550—pivoted on the end of the 100 bucket and having a connecting rod or link 556 pivoted to said rocker, and also pivoted to the closer in such a manner that when the closer is shut the two pivots of said connecting-rod or toggle member will be nearly in line 110 with and the upper of said pivots will be above the rocker-pivot, whereby when the rocker is engaged by the latch and held in that position the closer will be supported with a minimum pressure on the latch, as practically all of the 115 weight of the bucket contents will be carried on the pivot 550" of the rocker.

The closer-latch for locking the rocker in position when the closer is shut, and which is designated by 82, is shown herein as pivoted 120 at 87 on the end of the bucket and as having a detent or stop 81 in position and adapted for engaging a co-operating stop on the toggle connection when the parts are in the closed position previously described. This co-operating stop of the toggle connection is illustrated at 550' as carried on the rocker 550 and as substantially vertically superposed relatively to the pivot 550" when the closer is shut. It will be understood, of course, that 130 that end of the latch which engages the co-operating stop of the toggle connection is suitably weighted, so as to tend to normally engage such toggle-connection stop. As a means

for limiting the descent of this counterweighted detent end of the latch, the rocker 550 is shown as having a curved face, preferably defined by an arc struck from the pivot 550" as 5 a center and against which curved face said detent end of the latch is adapted to normally engage.

The organization of closer supporting and latching means which has just been described 10 is shown as duplicated, so that each end of the closer is supported and latched; but it is not essential that this mechanism should be so duplicated, especially in the smaller sizes of machines.

15 From the foregoing description of the bucket and its closing devices it will be obvious that the bucket has two members, one of which is shiftable relatively to the other for discharging the load, and that the bucket- 20 closer in the present case constitutes the shiftable bucket-discharge member and has a bucket-discharge movement controlled by the bucket-closer latch.

As it will be apparent that on the descent 25 of the bucket and the scale-beams all those points in said scale-beams which are between the bucket-supporting knife-edges or bucket-supports will have relatively-faster descending movements than those points in the 30 buckets which correspond in position with said points in the beams, it will be readily perceived that the closer-latch may be released by a properly-positioned stop carried by a scale-beam. Such a stop is shown at 88 as 35 carried on the scale-beam B', and the closer-latch is also shown as having a stop in position for co-operating with the stop on the scale-beam and adapted to be engaged to release the latch at a predetermined point in the descent 40 of the bucket and the beam, owing to the relatively-rapid movement of the beam-stop as compared with the movement of the stop on the closer-latch. I do not, however, limit 45 my present invention to the use of this particular kind of tripping-stop.

For the purpose of balancing the bucket in testing the poise of the balancing mechanisms without discharging the contents of the receptacle one of the latch-releasing stops 50 should have a relative movement out of the path of the other, in order that the closer-latch may remain operative to hold the bucket-closer against opening. In the present case I have shown the stop on the bucket- 55 closer latch as so movable and as comprising a swinging arm 557, pivoted at 557' to the latch and as having means for normally maintaining such stop in its operative position. The means which is shown herein for 60 obtaining this result is a spring, such as 557", secured to the closer-latch on that side of the latch-pivot which is opposite the counterweighted end of the latch, and the free end of this spring is shown as engaging the stop-arm 557 to normally hold the same in the path 65 of movement of the stop 88. When it is desired to permit the bucket and the beams to

descend without releasing the latch, the spring will be swung to one side and the stop-arm 557 swung over toward the pivot of the 70 bucket-latch.

As a means for controlling the stream from the supply-chute, I prefer to employ a valve substantially similar to that shown in my Patent No. 535,727, granted March 12, 1895. 75 I have shown such a valve at 70, pivoted within arms or brackets 5', depending from the top plate of the machine, the pivot or axis of movement of the valve being designated by 70'. The valve employed is also 80 illustrated as located substantially beneath the mouth of the supply-chute and as extending beyond the forward edge of said chute sufficiently far to support the descending column or stream when the valve is closed, 85 and the valve is also or may be counterweighted at its rear end, as at 90, so as to have a normal self-closing tendency. In the present case, therefore, this counterweight is shown as constituting a valve-closing actuator, or means for actuating the valve to close the same; but I do not limit myself to the use of any particular means for effecting such closing movement. In my said Patent No. 535,729, first hereinbefore referred to, I have 95 shown and described means for limiting or intercepting the opening movement of the valve while the closer is open, and for also limiting or intercepting the opening movement of the closer while the valve is open, in 100 connection with means for actuating the valve to open and close the same, independently of the operation of the bucket-closer, and in the present application I have retained this feature of a reciprocal control or mutual 105 dependency of the opening movements of the valve and the closer in an improved embodiment of the means for obtaining this result, whereby the controlling action is rendered 110 more perfectly sensitive.

In a divisional application, Serial No. 561,264, filed September 3, 1895, and concurrently pending herewith, and in connection with a valve and with a bucket and its closer, and with means for actuating the 115 valve independently of the operation of the closer, I have shown, described, and claimed a valve-stopping thrust member operative with the closer and independently of the operation of the valve and having an upward 120 thrust movement from and on the opening movement of the closer for intercepting the opening movement of the valve by said thrust movement, which combination constitutes the subject-matter of said divisional application. 125

The improved devices which I prefer to employ for reciprocally limiting the valve and closer movements will now be described.

The rocker 550 is shown herein as having 130 pivotally connected thereto at 417 a valve-stop or valve-stopping thrust member 415, and this stop or stop-arm is shown connected to the rocker in such a position that said stop

will have a relatively-rapid movement (illustrated herein as an upward-thrust movement) on and with respect to the opening movement of the bucket-closer, so that the friction-
 5 roller 413, which I have shown as constituting the stop proper, will have an accelerated thrust movement for intercepting the valve during the initial opening movement of the bucket-closer. In the absence of the friction-
 10 roller the end of the rod will, of course, constitute such stop. Owing to the peculiar manner in which the rocker, the closer, and the thrust member are connected, it will be obvious that on the opening of the closer
 15 the movement of said thrust member relatively to that of the closer, will be a multiplied one of decreasing ratio. The valve 70 is shown as also having a stop 412, provided with connected stop-faces 412' and 412'' in
 20 position and adapted to be engaged by the closer-operated valve-stop on the opening movement of the closer, the stop-face 412' being positioned relatively to the said closer-operated stop, so that such stop-face will be
 25 effective to limit or check the opening movement of the valve when the closer is released during the period while the valve is closed, the other stop-face 412'' being positioned relatively to the said closer-operated stop, so that
 30 such stop-face will act as a safety device to limit or prevent opening movement of the valve while the closer is open by limiting or checking the opening movement of the closer, if the closer-latch is released, during the
 35 period while the valve is actually open.

It will be apparent from the foregoing that the closer-supporting means modify the movements of the valve-stop or valve-stopping thrust member relatively to the opening
 40 movement of the closer, and that this modification is in the nature of an acceleration of the movement of such closer-operated stop or valve-stopping thrust member. Hence it will be evident also that the valve mechanism and
 45 the bucket-closer have two coacting stops, one of which is operative with the closer and the other of which is operative with the valve mechanism, and that these stops are so positioned that they reciprocally limit the movements of and serve as stop devices for each other, and that one of said stops, and preferably that operative with the closer, has a relatively rapid movement, preferably a thrust, on and with respect to the opening movement
 50 of the bucket-closer. In the embodiment thereof shown in the drawings this relatively rapid movement of the valve-stopping member is, as hereinbefore stated, effected by the closer-supporting means. By organizing
 55 these mutually dependent means or stops so that one of them will have a relatively rapid or accelerated movement, substantially as previously herein described, a very sensitive action of said means is obtained for reciprocally limiting the opening movement of the closer by the non-closing of the valve and the

opening movement of the valve by the non-closing of the closer.

The closer-supporting means, it will be observed, not only holds the closer against the pressure of the contents of the bucket, but also serves to actuate the valve-stop connected therewith, so as to project said stop into the path of the valve, and thereby limit the movement of said valve. As the force exerted by the valve upon this valve-stop is considerable, and as such force, if transmitted to the closer-supporting devices, might tend to prevent the proper operation of the connected parts, I deem it advisable to transmit the greater portion of the force, due to the reaction of the valve, to some relatively fixed portion of the machine, and in the present case the stop-arm 415 is illustrated as having a connecting link or rod 414', pivotally secured thereto at the point where the friction-roller 413 is located, and having said connecting-rod also pivotally secured to the framework at 414, so that the rod constitutes a thrust-transmitting member for relieving the stop-arm 415 of the thrust of the valve and directing said thrust against a thrust-receiving member, which, as just described, constitutes a portion of the fixed framing.

The valve 70 is shown in the drawings as having a connecting rod or arm 558 pivotally secured to the upper rear portion thereof and as having the lower end of said rod in position and adapted to be engaged by a valve-opening actuator, which will now be described, said connecting-rod 558 being also shown as having a pivotal connection, by means of a guide-link 559, with a relatively fixed portion of the machine, (herein shown as the framework adjacent to the rear of said machine.)

The connecting-rod 558 is illustrated as constituting the means for transmitting to the valve the valve-opening movement of a valve-actuator, and that valve-actuator which has for its function the operation of opening the valve to permit the flow of the supply-stream into the bucket is shown herein as pivotally mounted on one of the scale-beams, in the present instance the beam B. In the form thereof herein illustrated this valve-opening actuator consists of a lever 551, pivoted at 551' to the scale-beam B and counterweighted at its rear end. This actuator or counterweighted lever, which is shown as constituting and will also be hereinafter referred to as a "supplemental counterpoise" or "supplemental balancing" means, normally forms part of the bucket-counterpoising portion of the scale-beam B and therefore of the whole bucket-counterpoising mechanism, but is automatically shiftable onto the bucket-poising mechanism at a predetermined point in the movement, herein shown as the ascent of the bucket. As a means for normally maintaining this valve-opening actuator or supplemental balancing means as a portion of the

- counterpoise of the beam B, said beam is shown herein as having a stop 560, on which the said balancing means is normally supported. It will be evident, therefore, that the 5 lever 551 serves for one of the purposes of the machine as a valve-opening actuator and for another of the requirements of the machine it constitutes supplemental balancing means or a supplemental counterpoise.
- 10 It will be observed that the pivot 551' of the valve-opening actuator is shown located between the bucket-supports which are carried by the scale-beams so that any downward pressure exerted upon the inner end of 15 the actuating-lever 551 relatively to the bucket will oscillate the supplemental balancing means and that a very slight oscillatory movement will shift the same from the counterpoising mechanism of the machine 20 onto the poising mechanism thereof, and thereby not only add to the poising side of the beam a relatively considerable weight, but also subtract from the counterpoising side of the beam the same or substantially the 25 same amount of weight.

The connecting-rod 558 has been hereinbefore described as having its lower end in position and adapted to be engaged by a valve-opening actuator, and hence it will be evident 30 that the lever 551 constitutes the means for engaging said rod. When free to actuate the valve for opening the same, it will be apparent that this rod 558 forms part of the actuating means and therefore a part of the 35 valve-opening actuator; but when the opening movement of the valve is prevented it will also be evident that this rod forms a stop device for limiting or checking the valve-opening movement of the valve-actuator. 40 Moreover, it will be seen that in the present case the connecting-rod 558 and the scale-beam B form shifting means for engaging the supplemental balancing means and automatically shifting the same from the counterpoising to the poising side of the mechanism 45 at a predetermined point in the movement of the bucket.

From the preceding description of the operation of the bucket-closer latch and the 50 closer-supporting means and of the operation of the valve-stops 415 and 412, respectively, it will be apparent that reciprocally-effective valve-opening-movement and closer-opening-movement limiters are provided, the 55 former of which is shown at 415 as operative to limit or check the opening movement of the valve while the bucket-closer is open and the latter of which is illustrated at 412 as effective to reciprocally limit or check the opening movement of the closer, and hence the 60 bucket-discharge movement of the shiftable bucket-discharge member while the valve is open.

As it is necessary in the normal operation 65 of a weighing-machine of this general class that the valve-opening movement of the valve-opening actuator be prevented during

that period in which the load in the bucket is being made up, it will be evident that if the valve-opening-movement limiter is in its 70 operative position it will be impossible for the valve-opening actuator to be effective as such, as the rod 558 will engage said actuator and form a stop device for limiting or checking the valve-opening movement thereof; 75 also, that when not supported on the stop 560 and when not checked by the stop device controlled by the closing movement of the valve said valve-opening actuator will be operable as such. 80

The normal position of the valve mechanism in a weighing-machine as ordinarily constructed is that in which the full flow of the supply-stream into the bucket is permitted; and hence the actuator for opening the valve 85 is shown herein as of relatively-greater power or efficiency than the means for closing said valve. The valve-opening actuator is also illustrated in the present case as operative in opposition to the valve-closing means and 90 therefore in opposition to the closing movement of the valve. For the purpose of preventing the closing movement of the valve during that period in which the valve-opening actuator would ordinarily be effective it 95 will be obvious that in a machine such as described, having a valve-opening actuator operative in opposition to and of relatively greater power or efficiency than the means for closing the valve, a stop device located in- 100 termediate of the valve-opening actuator and the valve-closing means and forming an intermittently-fixed connection between the valve-closing means and the valve-opening actuator will be sufficient while in such fixed 105 position to hold the valve against any closing movement that can be exerted by the normal operation of the valve-closing means. The connecting-rod 558 therefore constitutes not only a stop device for checking the valve-opening movement of the valve-opening actuator during the period in which the valve-opening-movement limiter is in its operative position, but also a stop device for preventing 110 the closing movement of the valve during 115 the period beginning with the release of the valve-opening-movement limiter and ending with the commencement of the descent of the bucket and the scale-beams, it being apparent, of course, that the valve-opening movement of the valve-opening actuator is checked during the descent of the bucket and the beams, the stop 560 having been already described as provided for this purpose. 120

From the preceding description, read in connection with the drawings, it will also be obvious that the valve has its closing movement during the period in which the closer-opening-movement limiter is in its operative position, and that the valve-opening actuator has its 125 valve-opening movement alternating with the closing movement of the valve, and hence the valve-opening and valve-closing actuators are alternately effective. The connecting-rod 130

558 or some suitable means for limiting the closing movement of the valve and the valve-opening movement of the valve-opening actuator, and hence for limiting the valve-actuating movements of the valve-opening and valve-closing actuators, I term a "valve-movement" stop; and it will be seen that such a valve-movement stop is adapted for reciprocally limiting the closing movement of the valve and the valve-opening movement of the valve-opening actuator, and is therefore adapted for reciprocally limiting the valve-actuating movements of the valve-opening and valve-closing actuators, so that it will be impossible for the valve-closing movement to take place or for the valve-actuating movement of the valve-closing actuator to occur while the valve-opening actuator is operative as such.

20 While the valve-movement stop has been described as being connected with the valve and as movable relatively to the valve-opening actuator at the lower end of said stop, I do not limit myself to such a construction, 25 but consider as within the scope of my invention any means operated as a valve-movement stop, positioned and adapted to have the functions here stated.

As a means for controlling the drip-stream, 30 the valve is shown provided with a stop, and a detent is so positioned and adapted as to engage this stop and hold the valve against closing during the drip period.

For releasing the valve means are also provided controlled by the overpoise movement of the scale-beam for disengaging the detent from said valve-stop to permit the cut-off movement of the valve. A valve-stop for this purpose is shown at 418, and a detent 40 device adapted for engaging this valve-stop is shown as comprising a counterweighted lever 420, pivotally mounted at 420" on the framework of the machine and pivotally secured to a connecting-rod 420', carrying a 45 stop member or detent proper 419, adjacent to the stop 418 and in position and adapted for engaging this last-mentioned stop during the drip period.

As a means for guiding the detent in its 50 movements and for taking up the thrust of the valve, a guide-link or thrust-receiving member is shown at 419' as preferably pivoted at the point 414 to the frame of the machine, this pivotal point being that also, as 55 before described, of the guide-link 414'. The detent for engaging the valve-stop is therefore a swinging one and engages the valve-stop at a predetermined point in the movement of the valve, and the detent is also 60 shown as having a stop 419" in position for engagement by one of the scale-beams on the descent of said beam to a predetermined point, whereupon the detent will be carried out of the path of movement of the co-operating 65 valve-stop.

For the purpose of limiting the movement of the detent in one direction and holding

said detent in the path of movement of the co-operative valve-stop any suitable stop device, such as that shown at 422, may be employed.

A scale-arm is shown herein at 561 as carried by and movable with one of the scale-beams, in this instance the scale-beam B', and as adapted to carry a load-weight, which 75 is adapted to be slid from the poising to the counterpoising side of the scale-arm, and vice versa, to thereby simultaneously reduce the weight of one of the balancing mechanisms and increase the weight of the other. A load-weight adapted for this purpose is shown at 80 M, carried on the scale-arm 561, and as slideable thereon from end to end of the same. This load-weight is shown in Fig. 1 as having a slideway on its inner side, the walls of which 85 way are adapted to closely engage the four sides of the scale-arm, to thereby hold the load-weight securely against lateral movement during the operation of the machine. As a means for securing this weight in any 90 desired adjusted position on the scale-arm, I have shown in the drawings (see Fig. 3) a clamp-nut 562, engaging a locking-bolt 562', working in a slot 563 and having a transverse tongue 562" for engaging the inner side 95 of the scale-arm, and thus clamp the weight in place thereon. The scale-arm 561 is also shown in the drawings as provided with a scale, having a series of division-lines 561' extending transversely across one face of said 100 scale-arm to indicate any required graduations. The load-weight is also illustrated in the present instance as having a scale-face, such as 564, in parallelism with a diagonal line connecting the corresponding opposite 105 terminals of two adjacent division-lines on the scale-arm, and said scale-face is furnished with a vernier-scale 564', coinciding in length with this diagonal, the vernier or cross scale being graduated to represent any usual subdivisions of the unit indicated by the graduations on the scale-arm.

It will be evident that by means of such a load-weight as that just described the bucket may be poised when empty and the machine 115 may be adjusted for weighing different loads. When the weight is slid out on the poising end of the scale-arm to a point near the end thereof, it will poise or exactly balance the weight of the bucket and its mechanism, and when slid backward to about the position shown in dotted lines in Fig. 5, this position being approximately in alignment with the supporting mechanisms of the scale-beam, the weight becomes about neutral. If the weight 120 is carried beyond said knife-edges, toward the left in said figure, said weight is added to that of the counterpoise-beam. Relatively smaller loads may be balanced by sliding the load-weight to its intermediate positions, and it has 125 been found in practice that such a machine as herein shown and described may be successfully operated for weighing loads somewhat less than one-half of the maximum load.

The main and vernier scales permit the operator to ascertain the weight of a partial load, such as usually remains at the end of a predetermined period of operation of the machine, as when weighing from a bin, the material thus left in the bin being usually less than a full load. By sliding the load-weight carefully along the scale-arm the operator can ascertain at what point on said arm the weight will bring the mechanisms to the poise and can then read off the weight of the partial load. In this way the correct weight of any quantity of material may be ascertained, as it will be obvious that the point of intersection of the vernier scale-face with a graduation of the main scale will designate the true weight of the load.

The operation of a machine constructed in accordance with my invention, as hereinbefore set forth, will now be described.

With the parts in position shown in Figs. 3 and 4 (the normal position for the commencement of the weighing operation) the valve 70 is wide open and permits the uninterrupted flow of the stream issuing from the supply-chute H down into the bucket G. At this time the bucket-latch 82 is operative to hold the closer Lshut, and hence the valve-opening-movement limiter lies below and out of engagement with the stop 412, but in position to instantaneously rise and engage the closer-opening-movement limiter or stop 412, should the latch 82 be accidentally released prematurely. At this time, also, the closing movement of the valve is checked by the abutment of the valve-movement stop 558 against the valve-opening actuator 551, and the valve-opening actuator is inoperative as such, owing to the fact that it is stopped at the end of the range of movement of the bucket-counter-poising mechanism. As soon as the load is sufficiently made up to permit the descent of the bucket and the scale-beams, the valve-opening actuator, falling slowly from under the valve-movement stop, permits the valve-opening movement to begin, and at the same time the stop-face 412" is shifted relatively to the valve-opening-movement limiter until the detent-stop 419 engages the stop 418, carried by the valve, when said valve-opening-movement limiter will be at the extreme end of said stop-face 412" and in position to engage the stop-face 412' on the release of the detent 419, as shown in Fig. 5. The detent-releasing stop carried by the Scale-beam B is also shown as about to carry down the stop 419". During the time in which the valve is locked in the drip position by the detent the valve-movement stop rises from the valve-opening actuator, owing to the continuation of the descent of the beams, and on the release of the detent by the beam-stop or other detaching means the valve is quickly carried to the cut-off position shown in Fig. 6 and the valve-movement stop (which at the moment of the release of the detent was some distance above the valve-opening actuator) is thrown quickly

against said actuator, and the whole force exerted by the valve-counterweight 90 and the momentum of the rapidly-closed valve is thrown against and onto the valve-opening actuator, the valve-movement stop thus serving as a power-transmitting means, and an added impetus, due to the weight, momentum, and impact of said valve-operated means, is given to the bucket-poising mechanism to carry the same rapidly to the limit of the descending movement and thereby insure the release of the bucket-closer latch.

In Fig. 7 the bucket-closer latch is shown as having been released from engagement with the stop 550 on the toggle connection, owing to the actuation of the stop 557 by the stop 88, and the weight of the contents of the bucket has thrown open the closer, the first opening movement of said closer instantaneously carrying the valve-opening-movement limiter to its operative position and preventing the opening of the valve.

As soon as the proper portion of the load has been discharged from the bucket, the bucket and the scale-beams will of course tend to rise; but thereupon, owing to the fact that the valve-movement stop 558 is a rigid abutment by reason of the valve-opening-movement limiter 415 being in its operative position, the return of the valve-opening actuator will be prevented. If the valve-opening actuator is supplementary to the main counterpoise mechanism, which is the organization illustrated in the drawings, this supplemental counterpoise or actuator 551 will be held, as shown in Fig. 8, while the remainder of the balancing mechanism returns to the normal position; but if, as might be the case in small-sized machines, the main counterpoise mechanism constitutes the valve-opening actuator, then the whole balancing mechanism will of course be held against return movement. In small-sized machines, operating as thus described, the only change involved would be the substitution of a properly-positioned stop-face on the beam mechanism for the supplemental balancing means or actuator shown at 551. For this modification see Fig. 9, in which the roll 551" is shown carried by a pin 551'', fixed directly in the beam-arm 19'.

It will be apparent that the valve-opening actuator will be held inoperative as such by the valve-movement stop until the closer is entirely shut, as the valve-opening-movement limiter is not released from its engagement with the valve until the last part of this closer movement. As soon as the closer is completely shut, the bucket-closer latch 82 will re-engage the closer-supporting means and at the same moment, owing to the withdrawal of the valve-opening-movement limiter 415 on its return-stroke, the valve-opening actuator 551 becomes operable for reverse oscillatory movements, and, returning to its normal position, forces the valve open, and the valve-movement stop 558 is then operative to pre-

vent the closing of the valve until the beginning of a new cycle of movements, the closer-opening-movement limiter 412 being returned at the same time to its effective position.

5 It will be seen from the foregoing that all of the operations of such a weighing-machine as herein described are positively interdependent and that it is impossible for the movements of the valve and the closer and the 10 valve-opening actuator to take place in any other than a determined order so long as the machine is operatively organized. The valve-opening actuator is held ineffective by the valve-opening-movement limiter during the 15 effective action of said limiter, and hence has an ineffective period synchronous with the effective period of this limiter, and the valve-closing actuator is operable with the closer-opening-movement limiter and by the descent 20 of the scale-beam and is effective alternately with the valve-opening actuator. By having the valve-opening actuator oscillatory on and relatively to one of the scale-beams the operation of said actuator is rendered very sensitive, as on its release by the valve-movement 25 stop (which, as will be seen, is releasable in turn on the return stroke of the valve-opening-movement limiter,) a relatively-small resistance is opposed to the action of such valve-opening actuator. It will be noticed, also, 30 that while the valve-opening actuator is operable on one release of the valve-movement stop the valve-closing actuator is operable on the other release of said stop, so that the two 35 actuators are mutually dependent and are resistively connected.

Having thus described my invention, I claim—

1. In a weighing-machine, the combination 40 with a valve and with a bucket-closer; of reciprocally-effective, valve-opening-movement and closer-opening-movement limiters; and a valve-opening actuator, operable on the return stroke of the valve-opening-movement 45 limiter, and having an ineffective period synchronous with the effective period of said limiter, substantially as described, and for the purposes set forth.

2. In a weighing-machine, the combination 50 with a valve and with a bucket-closer; of reciprocally-effective, valve-opening-movement and closer-opening-movement limiters; and a valve-opening actuator, held ineffective by the valve-opening-movement limiter during the 55 effective action of said limiter, and operable on the return stroke of said limiter, substantially as described, and for the purposes set forth.

3. In a weighing-machine, the combination 60 with a valve having its closing movement during the period in which the closer-opening-movement limiter is in its operative position; and with a bucket-closer; of reciprocally-effective, valve-opening-movement and closer- 65 opening-movement limiters; and a valve-opening actuator operable on the return stroke of the valve-opening-movement lim-

iter, and having its valve-opening movement alternating with the closing movement of said valve, substantially as described, and for the 70 purposes set forth.

4. In a weighing-machine, the combination 75 with a valve and with a bucket-closer; and with reciprocally-effective, valve-opening movement and closer-opening-movement limiters; of alternately-effective valve-opening and valve-closing actuators, having the former operable on the return stroke of the valve-opening-movement limiter, and the latter operable with the closer-opening-movement lim- 80 iter, substantially as described, and for the purposes set forth.

5. In a weighing-machine, the combination 85 with a valve, a scale-beam and a bucket-closer; and with reciprocally-effective, valve-open- 90 ing-movement and closer-opening-movement limiters; of alternately-effective valve-opening and valve-closing actuators, having the former operable on the return stroke of the valve-opening-movement limiter, and the lat- 95 ter operable with the closer-opening-movement limiter, and by the descent of the scale-beam, substantially as described, and for the purposes set forth.

6. In a weighing-machine, the combination 95 with a valve and with a bucket-closer; and with reciprocally-effective, valve-opening-movement and closer-opening-movement limiters; of alternately-effective and mutually- 100 dependent valve-opening and valve-closing 105 actuators, operative in opposition to each other, and having the former operable on the return stroke of the valve-opening-movement limiter, and the latter operable with the closer-opening-movement limiter, substan- 110 tially as described, and for the purposes set forth.

7. In a weighing-machine, the combination 110 with a valve, a scale-beam, and a bucket- 115 closer; of reciprocally-effective, valve-open- 120 ing-movement and closer-opening-movement limiters; a valve-closing actuator operable with the closer-opening-movement limiter; and a valve-opening actuator effective alternately with the valve-closing actuator, and carried by the scale-beam, and operable on the return stroke of the valve-opening-movement limiter, and having its valve-opening movement relatively to said scale-beam, substan- 125 tially as described, and for the purposes set forth.

8. In a weighing-machine, the combination 125 with a valve, a scale-beam and a bucket- 130 closer; of reciprocally-effective, valve-open- 135 ing-movement and closer-opening-movement limiters; a valve-closing actuator operable with the closer-opening-movement limiter and by the descent of the scale-beam; and a valve-opening actuator effective alternately with the valve-closing actuator, and carried by the scale-beam, and operable on the return stroke of the valve-opening-movement limiter, and having its valve-opening move- 140 ment relatively to said scale-beam, substan-

tially as described, and for the purposes set forth.

9. In a weighing-machine, the combination with a valve; and with a shiftable bucket-discharge member having a bucket-discharge movement; of a limiter for the bucket-discharge movement of said bucket-discharge member; a valve-opening-movement limiter reciprocally effective with said bucket-discharge-movement limiter; and a valve-opening actuator operable on the return stroke of the valve-opening-movement limiter, and having an ineffective period synchronous with the effective period of said limiter, substantially as described, and for the purposes set forth.

10. In a weighing-machine, the combination with a valve, a scale-beam and a bucket-closer; of reciprocally-effective, valve-opening-movement and closer-opening-movement limiters; a valve-closing actuator operable with the closer-opening-movement limiter; a valve-opening actuator effective alternately with the valve-closing actuator, and carried by the scale-beam, and operable on the return stroke of the valve-opening-movement limiter, and having its valve-opening movement relatively to said scale-beam; and a stop on the scale-beam, and in position and adapted for normally preventing relative movement of the valve-opening actuator with respect to the scale-beam, substantially as described, and for the purposes set forth.

11. In a weighing-machine, the combination with a valve, a counterpoised scale-beam and a bucket-closer; of reciprocally-effective, valve-opening-movement and closer-opening-movement limiters; a valve-closing actuator operable with the closer-opening-movement limiter, and by the descent of the scale-beam; a valve-opening actuator effective alternately with the valve-closing actuator, and carried by the scale-beam, and normally forming part of the counterpoise for said beam, and operable on the return stroke of the valve-opening-movement limiter, and having its valve-opening-movement relatively to said scale-beam; and a stop on the scale-beam, and in position and adapted for normally preventing relative movement of the valve-opening actuator with respect to the scale-beam, substantially as described, and for the purposes set forth.

12. In a weighing-machine, the combination with a valve, a counterpoised scale-beam and a bucket-closer; of reciprocally-effective, valve-opening-movement and closer-opening-movement limiters; a valve-closing actuator operable with the closer-opening-movement limiter, and by the descent of the scale-beam; a valve-opening actuator effective alternately with the valve-closing actuator, and pivotally mounted on the scale-beam, and normally forming part of the counterpoise for said beam, and operable on the return stroke of the valve-opening-movement limiter, and having an oscillatory valve-opening movement relatively

to said scale-beam; and a stop on the scale-beam, and in position and adapted for normally preventing oscillatory movement of the valve-opening actuator relatively to the scale-beam, substantially as described, and for the purposes set forth.

13. In a weighing-machine, the combination with a valve, a scale-beam and a bucket-closer; of reciprocally-effective, valve-opening-movement and closer-opening-movement limiters; a valve-closing actuator operable with the closer-opening-movement limiter; and a valve-opening actuator effective alternately with, and of relatively-greater efficiency than, the valve-closing actuator, and carried by the scale-beam, and operable on the return stroke of the valve-opening-movement limiter, and having its valve-opening-movement relatively to said scale-beam, substantially as described, and for the purposes set forth.

14. In a weighing-machine, the combination with a valve, a scale-beam and a bucket-closer; of reciprocally-effective, valve-opening-movement and closer-opening-movement limiters; a valve-closing actuator operable with the closer-opening-movement limiter, and by the descent of the scale-beam; and a valve-opening actuator effective alternately with, and of relatively-greater efficiency than, the valve-closing actuator, and operative in opposition to said valve-closing actuator, and carried by the scale-beam, and operable on the return stroke of the valve-opening-movement limiter, and having its valve-opening-movement relatively to said scale-beam, and operable to its valve-opening position and relatively to the scale-beam by the ascent of said beam, substantially as described, and for the purposes set forth.

15. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the effective period of the valve-opening-movement limiter; a valve-closing actuator effective alternately with the valve-opening actuator, and operable with the closer-opening-movement limiter; and a valve-movement stop for the valve-opening actuator, and releasable on the return stroke of the valve-opening-movement limiter, and in position and adapted for engaging the valve-opening actuator during the period beginning with the final closing of the valve and ending with the subsequent release of the valve by the valve-opening-movement limiter, substantially as described, and for the purposes set forth.

16. In a weighing-machine, the combination with a valve, a scale-beam and a bucket-closer; of reciprocally-effective, valve-opening-movement and closer-opening-movement limiters; a valve-closing actuator operable with the closer-opening-movement limiter, and by the descent of the scale-beam; a valve-opening

- actuator effective alternately with, and of relatively-greater efficiency than, the valve-closing actuator, and operative in opposition to said valve-closing actuator, and carried by 5 the scale-beam, and operable on its release by the valve-movement stop, and having its valve-opening movement relatively to said scale-beam; and a valve-movement stop for the valve-opening actuator, and releasable on 10 the return stroke of the valve-opening-movement limiter, and in position and adapted for engaging the valve-opening actuator during the period beginning with the final closing of the valve and ending with the subsequent release 15 of the valve by the valve-opening-movement limiter, substantially as described, and for the purposes set forth.
17. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the 25 effective period of the valve-opening-movement limiter; a valve-closing actuator effective alternately with the valve-opening actuator, and operable with the closer-opening-movement limiter, and a valve-movement 30 stop for the valve-opening actuator, and releasable on the return stroke of the valve-opening-movement limiter, and in position and adapted for engaging the valve opening actuator during the period in which said limiter is in its operative position and preventing the valve-opening movement of the valve-opening actuator during said period, and for holding said valve-opening actuator in its valve-opening position relatively to the 35 scale-beam on the ascent of said beam, substantially as described, and for the purposes set forth.
18. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the 45 effective period of the valve-opening-movement limiter; a valve-closing actuator effective alternately with the valve-opening actuator, and operable with the closer-opening-movement limiter; and a valve-movement 50 stop for the valve-opening actuator, and releasable on the return stroke of the valve-opening-movement limiter, and carried by the valve, and in position and adapted for engaging the valve-opening actuator during the 55 period beginning with the final closing of the valve and ending with the subsequent release of the valve by the valve-opening-movement limiter, substantially as described, and for the purposes set forth.
19. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the effective period of the valve-opening-movement limiter; a valve-closing actuator effective alternately with the valve-opening actuator, and operable with the closer-opening-movement limiter; and a valve-movement 70 stop for the valve-opening actuator, and releasable on the return stroke of the valve-opening-movement limiter, and pivotally secured to the valve, and in position and 75 adapted for engaging the valve-opening actuator during the period beginning with the final closing of the valve and ending with the subsequent release of the valve by the valve-opening-movement limiter, substantially as described, and for the purposes set forth.
20. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the effective period of the valve-opening-movement limiter; a valve-closing actuator effective 85 alternately with the valve-opening actuator, and operable with the closer-opening-movement limiter; and a valve-movement stop for the valve-opening actuator, and releasable on the return stroke of the valve-opening-movement limiter, and pivotally secured to the valve, and having a swinging-guide pivoted to said valve-movement stop and to a fixed portion of the machine, and in position for engaging the valve-movement 90 stop with the valve-opening actuator during the period beginning with the final closing of the valve and ending with the subsequent release of the valve by the valve-opening-movement limiter, substantially as described, and for the purposes set forth.
21. In a weighing-machine, the combination with a valve and with a bucket-closer; of reciprocally-effective, valve-opening-movement and closer-opening-movement limiters; a valve-opening actuator operable on its release by the valve-movement stop, and having an ineffective period synchronous with the effective period of the valve-opening-movement limiter; a valve-closing actuator effective 95 alternately with the valve-opening actuator, and operable with the closer-opening-movement limiter; and a valve-movement stop for the valve-opening actuator, and releasable on the return stroke of the valve-opening-movement limiter, and fixed relatively to one of the valve-operating actuators, and in position and adapted for engaging the other of said valve-operating actuators during the period beginning with the final closing of the 100 valve and ending with the subsequent release of the valve by the valve-opening-movement limiter and preventing the valve-opening movement of said valve-opening actuator,

- substantially as described, and for the purposes set forth.
22. In a weighing-machine, the combination with a valve having its closing movement during the period in which the closer opening-movement limiter is in its operative position; and with a bucket-closer; of reciprocally-effective, valve-opening-movement and closer-opening-movement limiters; a valve-opening actuator operable on the return stroke of the valve-opening-movement limiter, and having its valve-actuating movement alternating with the closing movement of said valve; and a valve-movement stop in position and adapted for limiting the valve-actuating movement of the valve-opening actuator throughout the period beginning with the final closing of the valve and ending with the subsequent release of the valve by the valve-opening-movement limiter, substantially as described, and for the purposes set forth.
23. In a weighing-machine, the combination with a valve having its closing movement during the period in which the closer-opening-movement limiter is in its operative position; and with a bucket-closer; of reciprocally-effective, valve-opening-movement and closer-opening-movement limiters; a valve-opening actuator operable on the return stroke of the valve-opening-movement limiter; and a valve-movement stop in position and adapted for reciprocally limiting the closing movement of the valve and the valve-opening movement of the valve-actuator, substantially as described, and for the purposes set forth.
24. In a weighing-machine, the combination with a valve and with a bucket-closer; of reciprocally-effective, valve-opening-movement and closer-opening-movement limiters; a valve-opening actuator operable on the return stroke of the valve-opening-movement limiter; a valve-closing actuator operable with the closer-opening-movement limiter; and a valve-movement stop in position and adapted for reciprocally limiting the valve-actuating movements of the valve-opening and valve-closing actuators, substantially as described, and for the purposes set forth.
25. In a weighing-machine, the combination with a valve having its closing movement during the period in which the limiter for the bucket-discharge movement of the bucket-discharge member is in its operative position; and with a shiftable bucket-discharge member having a bucket-discharge movement; of a limiter for the bucket-discharge movement of said bucket-discharge member; a valve-opening-movement limiter reciprocally effective with said bucket-discharge-movement limiter; a valve-opening actuator operable on the return stroke of the valve-opening-movement limiter; and a valve-movement stop in position and adapted for reciprocally limiting the closing movement of the valve and the valve-opening movement of the valve-actuator, substantially as described, and for the purposes set forth.
26. In a weighing-machine, the combination with a valve, a scale-beam and a bucket-closer; of reciprocally-effective, valve-opening-movement and closer-opening-movement limiters; a valve-opening actuator operable on one release of the valve-movement stop, and having an ineffective period synchronous with the effective period of the valve-opening-movement limiter; a valve-closing actuator effective alternately with the valve-opening actuator, and operable with the closer-opening-movement limiter, and operable on the other release of the valve-movement stop; and a valve-movement stop alternately operable by the valve-operating actuators, and in position and adapted for reciprocally controlling the valve-operating movements of the valve-operating actuators, and having its aforesaid first-mentioned release on the return stroke of the valve-opening-movement limiter, and having its other release on the descent of the scale-beam, substantially as described, and for the purposes set forth.
27. In a weighing-machine embodying a scale-beam, the combination with a valve having its closing movement during the period in which the closer-opening-movement limiter is in its operative position; and with a bucket-closer; of reciprocally-effective, valve-opening-movement and closer-opening-movement limiters; a valve-opening actuator operable on the return stroke of the valve-opening-movement limiter, and having its valve-opening movement alternating with the closing movement of said valve; a stop carried by the valve; a detent in position and adapted for engaging said valve-stop and holding the valve against closure during the drip period; and means controlled by the overpoise movement of the scale-beam for releasing said detent and permitting the cut-off movement of the valve, substantially as described, and for the purposes set forth.
28. In a weighing-machine, the combination with a valve, a scale-beam and a bucket-closer; of reciprocally-effective, valve-opening-movement and closer-opening-movement limiters; a valve-closing actuator operable with the closer-opening-movement limiter; a valve-opening actuator effective alternately with the valve-closing actuator, and carried by the scale-beam, and operable on the return stroke of the valve-opening-movement limiter, and having its valve-opening movement relatively to said scale-beam; a stop carried by the valve; a detent in position and adapted for engaging said valve-stop and holding the valve against closure during the drip period; and means controlled by the overpoise movement of the scale-beam for releasing said detent and permitting the cut-off movement of the valve, substantially as described, and for the purposes set forth.
29. In a weighing-machine, the combination with a bucket and with a closer therefor; of the inverted toggle-connection joining said bucket and the closer for supporting the

closer, and having its members disposed at about the angle of repose of the connection when the closer is closed; and a closer-latch in position and adapted for engaging said toggle-connection and holding the same at about the angle of repose of the toggle-connection when the closer is closed, whereby when the closer is closed a relatively-great weight is supported on the bucket-pivot of said toggle-connection and a relatively-small weight is supported on the closer-latch, substantially as described.

30. In a weighing-machine, the combination with a bucket and with a closer therefor; of a rocker pivotally supported on the bucket, and above the closer; a connecting-rod pivoted to the closer for supporting the same, and also pivoted to the rocker, and having said pivots nearly in line with, and the latter of said pivots above, the rocker-pivot when the closer is closed; and a closer-latch in position and adapted for engaging said rocker and holding the same at about the angle of repose of the rocker and the connecting-rod when the closer is closed, whereby when the closer is closed a relatively-great weight is supported on the rocker-pivot and a relatively-small weight is sustained by the closer-latch, substantially as described.

31. In a weighing-machine, the combination with a bucket and with a closer therefor; of a rocker pivotally supported on the bucket, and above the closer; a connecting-rod pivoted to the closer for supporting the same, and also pivoted to the rocker, and having said pivots nearly in line with, and the latter of said pivots above, the rocker-pivot when the closer is closed; a closer-latch in position and adapted for engaging said rocker and the connecting-rod when the closer is closed, whereby when the closer is closed a relatively-great weight is supported on the rocker-pivot and a relatively-small weight is supported on the closer-latch; and means for releasing said closer-latch, substantially as described.

32. In a weighing-machine embodying a tripping-stop, in position and adapted for releasing the closer-latch on the descent of the scale-beam to a predetermined point; the combination with a bucket and with a closer therefor; of a rocker pivotally supported on the bucket, and above the closer; a connecting-rod pivoted to the closer for supporting the same, and also pivoted to the rocker, and having said pivots nearly in line with, and the latter of said pivots above, the rocker-pivot when the closer is closed; and a closer-latch releasable by the tripping-stop, and in position and adapted for engaging the rocker to hold the closer closed, whereby a relatively-large bucket-closer is supported with a minimum pressure on the closer-latch, substantially as described.

33. In a weighing-machine, the combination with a bucket and with a counterpoised scale-beam for supporting the bucket; of a closer for the bucket; a rocker pivotally supported

on the bucket and above the closer; a connecting-rod pivoted to the closer for supporting the same, and also pivoted to the rocker, and having said pivots nearly in line with, and the latter of said pivots above, the rocker-pivot when the closer is closed; a closer-latch in position and adapted for engaging the rocker to hold the closer closed, whereby a relatively-large bucket-closer is supported with a minimum pressure on the closer-latch; and a tripping-stop on the scale-beam, and in position and adapted for releasing the closer-latch on the descent of the scale-beam to a predetermined point, substantially as described.

34. In a weighing-machine, the combination with a bucket and with a pair of oppositely-disposed counterpoised scale-beams for supporting the bucket at points intermediate of the supporting pivots of said scale-beams; of a closer for the bucket; a rocker pivotally supported on the bucket, and above the closer; a connecting-rod pivoted to the closer for supporting the same, and also pivoted to the rocker, and having said pivots nearly in line with, and the latter of said pivots above, the rocker-pivot when the closer is closed; a closer-latch in position and adapted for engaging the rocker to hold the closer closed, whereby a relatively-large bucket-closer is supported with a minimum pressure on the closer-latch; and a tripping-stop on one of the scale beams, and in position and adapted for releasing the closer-latch on the descent of said scale-beam to a predetermined point, substantially as described.

35. In a weighing-machine embodying a stop normally in position and adapted for engaging the stop on the bucket-closer latch at a predetermined point in the descent of the scale-beam, the combination with a counterpoised scale-beam for supporting the bucket; of a bucket-closer; an inverted toggle-connection joining said bucket and closer for supporting the closer; and a bucket-closer latch in position and adapted for engaging said toggle-connection and holding the same at about the angle of repose of the toggle-connection when the closer is closed, and said latch having a stop normally in position and adapted to be engaged by the first-mentioned stop on the descent of the beam to the aforesaid predetermined point and to release the latch, and one of said stops having a relative movement out of the path of the other, substantially as described.

36. In a weighing-machine, the combination with a bucket; and with a counterpoised scale-beam for supporting the bucket, and having a stop normally in position and adapted for engaging the stop of the bucket-closer latch at a predetermined point in the descent of the scale-beam; of a bucket-closer; an inverted toggle-connection joining said bucket and the closer for supporting the closer; and a bucket-closer latch in position and adapted for engaging said toggle-connec-

tion and holding the same at about the angle of repose of the toggle-connection when the closer is closed, and said latch having a stop normally in position and adapted to be engaged by the stop on the scale-beam on the descent of the beam to the aforesaid predetermined point and to release the latch, and one of said stops having a relative movement out of the path of the other, substantially as described.

37. In a weighing-machine, the combination with a bucket; and with a counterpoised scale-beam for supporting the bucket, and having a fixed stop in position and adapted for engaging the stop of the bucket-closer latch at a predetermined point in the descent of the scale-beam; of a bucket-closer; an inverted toggle-connection joining said bucket and the closer for supporting the closer; and a bucket-closer latch in position and adapted for engaging said toggle-connection and holding the same at about the angle of repose of the toggle-connection when the closer is closed, and said latch having a stop movable with, and relatively to, the latch, and also having said stop normally in position and adapted to be engaged by the stop on the scale-beam on the descent of the beam to the aforesaid predetermined point and to release the latch, and said latch having a spring for holding the stop carried by the latch in its normal position against movement relatively to the latch, substantially as described.

38. In a weighing-machine, the combination with a valve; and with a bucket having a closer, and also having supporting means for holding said closer in its closed position and modifying the ratio of movement of the valve-stop relatively to the closer at successive points in the movements of said valve-stop and closer; of means for actuating the valve independently of the operation of the closer; and a valve-stop operative with the closer-supporting means and independently of the operation of the valve, and in position and adapted for intercepting the opening movement of the valve by a thrust movement, substantially as described.

39. In a weighing-machine, the combination with a valve and with a bucket having a closer, and also having supporting means for holding said closer in its closed position and modifying the ratio of movement of the valve-stopping thrust-member relatively to the closer at successive points in the movements of said valve-stopping thrust-member and the closer; of means for actuating the valve independently of the operation of the closer; and a valve-stopping closer-controlled thrust-member operative independently of the operation of the valve, and having an upward-thrust movement on the opening of the closer, substantially as described.

40. In a weighing-machine, the combination with a valve; and with a bucket having a closer, and also having supporting means for holding said closer in its closed position and

imparting a relatively-rapid movement to the valve-stopping thrust-member on the opening of the closer; of means for actuating the valve independently of the operation of the closer; and a valve-stopping thrust-member operative with the closer-supporting means and independently of the operation of the valve, and having a relatively-rapid upward-thrust movement from the closer-supporting means on, and with respect to, the opening movement of the closer, and in position and adapted for intercepting the opening movement of the valve by said thrust movement, substantially as described.

41. In a weighing-machine, the combination with a bucket having a closer; and with a valve; of means for actuating the valve to open and close the same independently of the operation of the bucket-closer; and mutually-dependent means operative respectively with the valve and with the closer for reciprocally limiting the opening movement of the closer by the non-closing of the valve and the opening of the valve by the non-closing of the closer, and one of said mutually-dependent means having a multiplied movement of decreasing ratio on, and with respect to, the opening movement of the closer.

42. In a weighing-machine, the combination with a bucket having a closer; and with a valve; of means for actuating the valve to open and close the same independently of the operation of the bucket-closer; and mutually-dependent means operative respectively with the valve and with the closer for reciprocally limiting the opening movement of the closer by the non-closing of the valve and the opening of the valve by the non-closing of the closer, and the latter of said mutually-dependent means having a relatively-rapid upward-thrust movement on, and with respect to, the opening movement of the closer.

43. In a weighing-machine, the combination with a bucket having a closer; and with a valve; of means for actuating the valve to open and close the same independently of the operation of the bucket-closer; and mutually-dependent means operative, respectively, with the valve and with the closer for reciprocally limiting the opening movement of the closer by the non-closing of the valve and the opening of the valve by the non-closing of the closer, and the latter of said mutually-dependent means having a multiplied upward-thrust movement of decreasing ratio on, and with respect to, the opening movement of the closer.

44. In a weighing-machine, the combination with a valve mechanism; and with a bucket having a closer; of two coacting-stops operative, respectively, with the valve and with the closer, for reciprocally limiting the movements of each other, and one of said stops having a multiplied movement of decreasing ratio on, and with respect to, the opening movement of the closer.

45. In a weighing-machine, the combination

with a valve mechanism; and with a bucket having a closer; of two coating-stops operative respectively, with the valve and with the closer, for reciprocally limiting the movements of each other, and the latter of said stops having a relatively-rapid upward-thrust movement on, and with respect to, the opening movement of the closer.

46. In a weighing-machine embodying a thrust-receiving member, the combination with a valve and with a bucket-closer; of a valve-opening-movement limiter connected with the closer-supporting means, and also connected with said thrust-receiving member, and in position and adapted for receiving the thrust of the valve during the effective period of said limiter, whereby the thrust of the valve is transmitted, in part, directly to the aforesaid thrust-receiving member; and closer-supporting means for holding said closer in its closed position and imparting a relatively-rapid movement to the valve-opening-movement limiter on, and with respect to, the opening movement of the closer, substantially as described.

47. In a weighing-machine embodying a tripping-stop in position and adapted for releasing the closer-latch on the descent of the scale-beam to a predetermined point; the combination with a bucket; and with a closer therefor; of a rocker pivotally supported on the bucket and above the closer; a connecting-rod pivoted to the closer for supporting the same, and also pivoted to the rocker, and having said pivots nearly in line with, and the latter of said pivots above, the rocker-pivot when the closer is closed; a closer-latch releasable by the tripping-stop, and in position and adapted for engaging the rocker to hold the closer closed; and a valve-opening-movement limiter operative on the opening of the closer, and connected with the rocker in position to have a relatively-rapid movement on, and with respect to, the opening movement of the closer, substantially as described.

48. In a weighing-machine embodying a bucket and bucket-counterpoising mechanism, and also embodying a bucket-poising mechanism supporting said bucket; the combination with supplemental balancing means normally carried by the bucket-counterpoising mechanism; of shifting means in position and adapted for automatically shifting said supplemental balancing means from off of said bucket-counterpoising mechanism and on to the bucket-poising mechanism at a predetermined point in the movement of the bucket.

49. In a weighing-machine embodying a bucket and bucket-counterpoising mechanism, and also embodying bucket poising mechanism supporting said bucket; the combination with pivoted supplemental balancing means normally carried by the bucket-counterpoising mechanism, and having the pivot of said supplemental balancing means on the bucket-poising mechanism; of shifting means

in position and adapted for engaging said supplemental balancing means at a predetermined point in the movement of the bucket, and for automatically oscillating said supplemental balancing means about the pivot thereof, and shifting said supplemental balancing means off of said bucket-counterpoising mechanism and on to the bucket-poising mechanism.

50. In a weighing-machine, the combination with oppositely-disposed beam-supports; of a pair of oppositely-disposed counterweighted-beams pivotally mounted on said supports, and having a pair of bucket-supports intermediate of, and adjacent respectively to, said beam-supports; means for maintaining the movements of said beams in unison; a bucket pivotally mounted on said bucket-supports; and supplemental balancing means carried by one of said beams, and normally counterpoising the bucket, and automatically shiftable from the bucket-counterpoising to the bucket-poising side of said beam at a predetermined point in the movement of the bucket.

51. In a weighing-machine embodying a bucket, and also embodying a pivotally-supported and counterpoised scale-beam supporting said bucket at the poising side of the axis of said beam; the combination with supplemental balancing means normally carried at the counterpoising side of the axis of said scale-beam; of shifting means in position and adapted for automatically shifting said supplemental balancing means from the normal position thereof and onto the poising side of said scale-beam at a predetermined point in the movement of the bucket.

52. In a weighing-machine, the combination with oppositely-disposed beam-supports; of a pair of oppositely-disposed counterweighted-beams pivotally mounted on said supports, and having a pair of bucket-supports intermediate of, and adjacent respectively to, said beam-supports, and one of said beams having a stop; means for maintaining the movements of said beams in unison; a bucket pivotally mounted on said bucket-supports; and supplemental balancing means pivoted on the stop-carrying beam intermediate of the bucket-supports, and normally engaging the stop on said beam to thereby form part of the counterpoise for said beam, and automatically oscillatory relatively to said beam at a predetermined point in the movement of the bucket to thereby shift said supplemental balancing means from the bucket-counterpoising to the bucket-poising side of said beam.

53. In a weighing-machine, the combination with a valve having its closing movement during the period in which the closer-opening-movement limiter is in its operative position; and with a bucket-closer; of reciprocally-effective, valve-opening movement and closer-opening-movement limiters; oppositely-disposed beam-supports; a pair of oppositely-disposed counterweighted-beams pivotally mounted on said supports, and having a pair of bucket-supports intermediate of, and ad-

jacent respectively to, said beam-supports, and one of said beams having a stop; means for maintaining the movements of said beams in unison; a bucket pivotally mounted on 5 said bucket-supports; and a combined supplemental balancing means and valve-opening actuator pivoted on the stop-carrying beam, intermediate of the bucket-supports, and normally engaging the stop on said beam, 10 to thereby form part of the counterpoise for said beam, and automatically oscillatory relatively to said beam on the movement of the bucket to thereby shift said supplemental balancing means from the bucket-counterpois- 15 ing to the bucket-poising side of said beam, and reversely-oscillatory for opening the valve on the return stroke of the valve-opening-movement limiter, and having its valve-opening movement alternating with the closing 20 movement of the valve, substantially as described, and for the purposes set forth.

54. In a weighing-machine, the combination with beam-supports; of a pair of oppositely-disposed counterweighted beams pivotally 25 mounted on said supports, and having a pair of bucket-supports intermediate of, and adjacent respectively to, said beam-supports; means for maintaining the movements of said beams in unison; a bucket pivotally mounted 30 on said bucket-supports; a supply-chute above the bucket; a valve for controlling the stream from the chute; a closer for the bucket; reciprocally-effective, valve-opening-movement and closer-opening-movement limiters; 35 and alternately-effective valve-opening and valve-closing actuators having the former operable on the return stroke of the valve-opening-movement limiter and the latter operable with the closer-opening-movement 40 limiter, substantially as described, and for the purposes set forth.

55. In a weighing-machine, the combination with two pairs of beam-supports; of a pair of oppositely-disposed beams, each embody- 45 ing a pair of beam-arms pivotally mounted on the corresponding pair of said beam-supports and a combined connecting-shaft and counterweight joining said beam-arms, said beam-arms each having a bucket-support interme- 50 diate of the beam-supports and adjacent to the corresponding beam-support; a connecting-link pivotally secured to oppositely-disposed beam-arms for maintaining the movements of the beam-arms in unison; and a 55 bucket pivotally mounted on said bucket-supports at opposite sides of its center, substantially as described.

56. In a weighing-machine, the combination with beam-supports; of a pair of oppositely-disposed counterweighted beams pivotally 60 mounted on said supports, and having a pair of bucket-supports intermediate of, and adjacent respectively to, said beam-supports, and also having a guide-connection for maintain- 65 ing the movements of said beams in unison; a bucket pivotally mounted on said bucket-supports; a supply-chute above the bucket;

a valve for controlling the stream from the chute; a closer for the bucket; reciprocally-effective valve-opening-movement and closer-opening-movement limiters; a valve-closing actuator carried by, and oscillatory with, the valve, and operable with the closer-opening-movement limiter; an oscillatory valve-opening actuator carried by one of said beams, 75 and having its pivot on the bucket-poising portion of said beam, and normally forming part of the bucket-counterpoising portion of the beam, and automatically oscillatory about its pivot at a predetermined point in the move- 80 ment of the bucket, and thereby shiftable off of the bucket-counterpoising side of said beam and on to the bucket-poising side of the beam, and reversely oscillatory for opening the valve on the return stroke of the valve-opening-movement limiter; and a valve-move- 85 ment step pivotally secured to the valve, and in position and adapted for reciprocally limiting the valve-actuating movements of the valve-opening and valve-closing actuators, 90 substantially as described.

57. In a weighing-machine, the combination with a beam-support; of a counterweighted-beam pivotally mounted on said support, and having a stop relatively remote from the pivot 95 of the beam and on the bucket-poising side of said beam, and also having a bucket-support intermediate of said stop and the pivot of the beam; a bucket pivotally mounted on said bucket-support; a closer for the bucket; and 100 a latch for holding the closer closed, and in position and adapted to be engaged and released by the beam-stop at a predetermined point in the descent of the beam and the bucket, substantially as described. 105

58. In a weighing-machine, the combination with a valve, having a stop; of a detent in position and adapted for engaging said valve-stop and holding the valve against closure during the drip period; means controlled by 110 the overpoise movement of the scale-beam for releasing said detent, and permitting the cut-off movement of the valve; power-transmitting means intermediate of the valve and the scale-beam, and in position and adapted 115 for transmitting the force of the valve to the scale-beam on the release of the detent, to thereby impart an added impetus to the descent of the scale-beam for unlatching the closer; a beam-support; a counterweighted 120 scale-beam pivotally mounted on said support, and having a stop relatively remote from the pivot of the beam and on the bucket-poising side of the beam; and also having a bucket- 125 support intermediate of said stop and the pivot of the beam; a bucket pivotally mounted on said bucket-support; a closer for the bucket; and a latch for holding the closer closed, and in position and adapted to be engaged and released by the beam-stop at a pre- 130 determined point in the descent of the beam and the bucket, substantially as described.

59. In a weighing-machine, the combination with beam-supports; of oppositely-disposed

- counterweighted-beams pivotally mounted on said supports, and having a pair of bucket-supports intermediate of, and adjacent respectively to, said beam-supports; means for maintaining the movements of said beams in unison; a bucket pivotally mounted on said bucket-supports; a closer for the bucket; a latch for holding the closer closed; and a stop carried by one of said scale-beams, and intermediate of the bucket-supports of oppositely-disposed beams, and adapted thereby to have a relatively-rapid movement with respect to the closer-latch on the descent of the bucket, and in position and adapted for engaging said latch and releasing the same at a predetermined point in the descent of the bucket, substantially as described.
60. In a weighing-machine, the combination with two pairs of beam-supports; of oppositely-disposed counterweighted-beams pivotally mounted on said supports, and having two pairs of bucket-supports intermediate of, and adjacent respectively to, said beam-supports; means for maintaining the movements of said beam in unison; a bucket pivotally mounted on said bucket-supports at opposite sides of its center; a closer for the bucket; a latch for holding the closer closed; and a stop carried by one of said scale-beams, and intermediate of the bucket-supports of oppositely-disposed beams, and adapted thereby to have a relatively-rapid movement with respect to the closer-latch on the descent of the bucket, and in position and adapted for engaging said latch and releasing the same at a predetermined point in the descent of the bucket, substantially as described.
61. In a weighing-machine, the combination with beam-supports; of oppositely-disposed counterweighted beams pivotally mounted on said supports, and having a pair of bucket-supports intermediate of, and adjacent respectively to, said beam supports, and one of said beams having a stop; means for maintaining the movements of said beams in unison; a bucket pivotally mounted on said bucket-supports; a supply-chute above the bucket; valve mechanism for controlling the stream from the chute; a closer for the bucket; a latch for holding the closer closed, and in position and adapted to be released by the stop on the beam on the descent of said stop to a predetermined point; and a stop on the bucket, and in position and adapted to engage one of said beams at a predetermined point in the ascent thereof, and thereby simultaneously check the ascent of both of the beams and of the bucket, substantially as described.
62. In a weighing-machine, the combination with beam-supports; of oppositely-disposed counterweighted-beams pivotally mounted on said supports, and having a pair of bucket-supports intermediate of, and adjacent respectively to, said beam-supports, and one of said beams having a stop; a bucket pivotally mounted on said bucket-supports; a supply-chute above the bucket; valve-mechanism for controlling the stream from the chute; a closer for the bucket; a latch for holding the closer closed, and in position and adapted to be released by the stop on the beam on the descent of said stop to a predetermined point; and a stop on the bucket, and in position and adapted to engage one of the beams at a predetermined point in the ascent thereof, and thereby simultaneously check the ascent of both of the beams and of the bucket, substantially as described.
63. In a weighing-machine, the combination with beam-supports; of oppositely-disposed counterweighted-beams pivotally mounted on said supports, and having a pair of bucket-supports intermediate of, and adjacent respectively to, said beam-supports; a bucket pivotally mounted on said bucket-supports; a supply-chute above the bucket; a valve for controlling the stream from the chute, and having its closing movement during the period in which the closer-opening-movement limiter is in its operative position; a closer for the bucket; reciprocally-effective, valve-opening-movement and closer-opening-movement limiters; and a valve-opening actuator operable on the return stroke of the valve-opening limiter, and having its valve-opening movement alternating with the closing movement of said valve, substantially as described, and for the purposes set forth.
64. In a weighing-machine, the combination with beam-supports; of oppositely-disposed counterweighted-beams pivotally mounted on said supports, and having a pair of bucket-supports intermediate of, and adjacent respectively to, said beam-supports; a bucket pivotally mounted on said bucket-supports; a supply-chute above the bucket; a valve for controlling the stream from the chute; a closer for the bucket; reciprocally-effective, valve-opening-movement and closer-opening-movement limiters; and alternately-effective valve-opening and valve-closing actuators having the former operable on the return-stroke of the valve-opening-movement limiter, and the latter operable with the closer-opening-movement limiter, substantially as described, and for the purposes set forth.
65. In a weighing-machine, the combination with beam-supports; of a pair of oppositely-disposed counterweighted beams pivotally mounted on said supports, and having a pair of bucket-supports intermediate of, and adjacent respectively to, said beam-supports; means for maintaining the movements of said beams in unison; a bucket pivotally mounted on said bucket-supports; a supply-chute above the bucket; a valve for controlling the stream from the chute, and having its closing movement during the period in which the closer-opening-movement limiter is in its operative position; a closer for the bucket; reciprocally-effective valve-opening-movement and closer-opening-movement limiters; a stop carried by one of the beams, and intermediate of the bucket-supports of oppositely-disposed beams, and adapted thereby to have a relatively-rapid movement with respect to the closer-opening-movement limiter on the descent of the bucket, and in position and adapted for

engaging said limiter and releasing the same at a predetermined point in the descent of the bucket; a valve-opening actuator operable on the return stroke of the valve-opening-movement limiter; and a valve-movement stop in position and adapted for reciprocally limiting the closing movement of the valve

and the valve-opening movement of the valve-actuator, substantially as described, and for the purposes set forth.
